UNITED STATES PATENT OFFICE.

JOHN E. EISELE, OF TAMPA, FLORIDA.

WINDOW-JAMB MACHINE.

1,074,355.

Specification of Letters Patent. Patented Sept. 30, 1913.

Application filed September 12, 1912. Serial No. 720,979.

To all whom it may concern:

Be it known that I, JOHN E. EISELE, a citizen of the United States, and a resident of Tampa, in the county of Hillsboro and State of Florida, have made certain new and useful Improvements in Window-Jamb Machines, of which the following is a specification.

My invention relates to improvements in devices for making sides of window and door jambs, and it consists in the combinations, constructions, and arrangements herein described and claimed.

An object of my invention is to provide a device which will dado both ends and cut pockets and pulley openings simultaneously.

A further object of my invention is to provide a device which will work on right and left jambs at the same time.

Other objects and advantages will appear in the following specification, and the novel features of the device will be particularly pointed out in the appended claims.

My invention is illustrated in the accompanying drawings forming part of this application in which similar reference characters indicate like parts in the several views, and in which—

Figure 1 is a side view of the machine, Fig. 2 is a plan view thereof, Fig. 3 is a sectional view on the line 3—3 of Fig. 9, showing one of the clamping devices in its operative position, Fig. 4 is a view similar to Fig. 3, showing the clamping device in its inoperative position, Fig. 5 is a sectional view on the line 5—5 of Fig. 4, Fig. 6 is a plan view of the end of the machine with one of the upper boards removed, Fig. 7 is a side view of the boring mechanism, Fig. 8 is an enlarged section through a portion of the boring device shown in Fig. 7, Fig. 9 is a face view of a slidable carrier, Fig. 10 is a sectional view along the line 10—10 of Fig. 9, Fig. 11 is a view partly in section of the diagonal dado cutter, Fig. 12 is a perspective view looking toward the rear of the longitudinal saw frame of the pocket cutting device, Fig. 13 is a perspective view showing the right and left hand boards of a window jamb, and the manner in which they are cut by the machine, Fig. 14 is a side view of the pocket cutting attachment, Fig. 15 is a sectional view on the line 15—15 of Fig. 14, Fig. 16 is a plan view of the pocket cutting attachment, and Fig. 17 is a sectional view along the line 17—17 of Fig. 16.

Referring now to Fig. 1, I have shown therein a main frame 1, upon which is journaled a shaft having a power wheel 3. The top board of the frame is formed by a bed plate 4 having rack teeth 5 on its lower side near one end of the machine. These rack teeth are for the purpose of coöperating with a pinion 6 (see Figs. 3 and 9) which is operated by a handle 7. Slidably carried by the bed plate 4 is a carriage 8. This carriage has a portion which extends downwardly and surrounds the shaft 2. An eccentric 9 is mounted on the shaft 2, and is keyed thereto so as to slide longitudinally of the shaft, but to be operated through the rotation of the latter. A gear 10 is also keyed to the shaft in a manner to slide longitudinally therewith and is arranged to mesh with a gear 11 on a shaft 12 journaled on the carriage 8.

Referring now to Figs. 9 and 10, it will be seen that the eccentric 9 is connected by a rod 13 with a bell-crank lever 14. The latter is connected to a reciprocating slide member 15 bearing upper saws 16 and lower saws 17. The device is so arranged that when the eccentric is in motion the slide 15 reciprocates so as to cause the reciprocating movement of the saws.

The means for holding the boards which form the jambs is best shown in Figs. 3 to 5 inclusive. As will be seen from Fig. 3 there are four jaws, 18, 18^x, 19 and 19^x, respectively. These jaws are pivoted on a common pivot 20 carried by the extension 8^x of the carriage 8. A spring 21 is disposed between the jaws 18^x and 19^x. A spring 22 is disposed between the jaws 18 and 18^x, while a spring 23 is disposed between the jaws 19 and 19^x. As will be seen from Fig. 2 there are three sets of these clamping devices disposed at A, B and C respectively. A common rod 24 extends through brackets 25 carried on the upper member of the jaws. Each clamping device is provided with an arm 26 (see Fig. 3) which is secured to the shaft 24, and which has a pivotal connection with the link 27 connected with the lower jaw 19. A rigid abutment member 28 extends forwardly from the carriage, i. e., in the opposite direction from the extension 18^x. This abutment member supports the inner jaws in their operative position.

The boards for forming a door or window jamb, such as those shown at 29 and 30 in Fig. 4, are placed on the members 19 and 18^x

and are pushed inwardly until they strike the stop members 31. The two inner jaws are held apart by means of the spring 21, and the outer jaws are kept apart by means 5 of the springs 22 and 23. Now if any one of the handles 33, which are on the square rod (see Fig. 1) be thrown into the position shown in dotted lines in Fig. 3, the jaws will be forced together so as to clamp 10 the boards in the horizontal position shown in the figure. It will be noted that in this movement the boards are brought nearer together. While they are being moved together they are operated on by the cutting 15 mechanism, as will be hereinafter explained.

Referring now to Figs. 6, 7 and 8, it will be seen that the shaft 12, which, as stated before, is operated through the medium of the gears 11 and 10, bears a gear 34 carried 20 between the links 35 and arranged to mesh with the gear 36, which is also disposed between the links 35 and between a pair of outer links 35^x. The gear 36 meshes with a gear 37, which has integral boring members 25 38 and 38^x extending from it. One end of the links 35^x is pivotally mounted on the boring devices 38 and 38^x, while a frame 41 is also pivotally mounted on the boring devices 38 and 38^x. This frame carries a 30 second gear 39, meshing with the gear 37 and is provided with boring devices 40 and 40^x. A handle 41^x is provided for manipulating the frame. Arranged to pass through bosses on the frame are the guide 35 members 42. Referring now to the clamping mechanism, it will be noted that when the lever 33 is shifted the boards are brought together in the manner described. As will be seen in Fig. 7, the boring tools will bore 40 holes in the boards as they are brought together by the clamping device. Now if the handle 41^x is shifted laterally into the dotted line position shown in Fig. 6, these boring devices, which are also cutters, will 45 cut longitudinal openings, such as those shown at 43 in Figs. 6 and 13. In order to get a clean cut the boring tools may be moved backwardly and forwardly by the handle 41^x until the desired result is obtained.

It will be noted that the reciprocation of the saws 16 and 17 is occasioned through the eccentric 9 and the members 14, 15 and 16, as already explained. When therefore 55 the boards 29 and 30 are brought down upon the saws, the latter will cut channels in the boards transverse to the longitudinal axis thereof. In Fig. 6, I have shown the upper saws 16. I may arrange transverse teeth 60 16^x between these saws, so as to cut out the material between the two saw kerfs formed by the saws 16. If desired these teeth 16^x may be omitted and the material may be removed by hand. There are two of 65 these dado cutting devices. In Fig. 11 I

have shown an oblique or diagonal dado cutter. In this figure the eccentric 9^y on the shaft 2 is connected by means of a rod 13^y with a bell-crank lever 14^y connected with a reciprocating carrier 15^y having upper and lower saws 16^y and 17^y respectively. The frame 45 which carries the reciprocating member 15^y is pivotally mounted upon a bracket 46 carried by the table 4. This support 45 is slotted at 45^x (see Fig. 2) and is 70 provided with locking bolts 47, which may be tightened to turn the support at any desired angle. In view of the fact that the rod 13^y is coincident with the axis of rotation of the support 45, the dado cutter may 75 be moved to any suitable angle and the eccentric 9^y will still operate to drive it.

Referring again to Fig. 1, it will be seen that on the shaft 2 is a third eccentric 48, which is connected by means of a rod 49 (see Fig. 14) to the swivel joint 50, attached to a shaft or rod 51 which slides in a vertical bearing 52 carried by a frame 53 secured to the bed plate 4. The rod 51 has two pivoted connecting rods secured to it. One of these connecting rods 54 is on one side of the rod 51 and the other 55 is on the other side (see Figs. 14, 15, 16 and 17). The connecting rod or pitman 54 drives a crank shaft 56 (see Fig. 16) while the connecting rod or pitman 55 drives a crank shaft 57 at right angles to the shaft 56. The crank shaft 56 is provided with the cranks 56^a and 56^b (see Fig. 16) to which the rods 56^c and 56^d are attached respectively. The rod 56^c is arranged to reciprocate a frame 58, which is carried by a central support 59 (see Fig. 6). The frame 58 is provided with upper and lower saws 60 and 61 respectively. The crank shaft 56 is extended through the support 59, and the crank 56^b reciprocates a frame 62, bearing upper and lower saws 60 and 61. It will be seen from Fig. 16 that the frames 58 and 62 are 180° apart in their reciprocatory movement. In other words, when one frame is going in one direction the other frame is going in the opposite direction.

The crank shaft 57 is connected by means of links 63 and 64 to the slidable frames 65 and 66 respectively (see Fig. 16). A description of one of these frames and the saws which they bear is sufficient, since they are both alike. Referring then to Fig. 14, it will be seen that the frame 65 is slidable in 110 a guide 67. Pivotally secured to the frame 65 are arms 68 and 69 which bear saws 68^x and 69^x respectively for cutting the ends of the pockets. Secured to the frame 65 itself are the saws 68^y and 69^y. The means for 115 opening the arms 68 and 69 to receive the boards 29 and 30 consists of a lever handle 70 mounted on a shaft 71 and connected by a link 72 with a lever 73, the end of which bears on the end portion of the arm 68. The 120 125 130

lever 73 is connected in turn by means of the links 74 with a bell-crank lever 75 whose end bears on the upper portion of the arm 69. It will be apparent that when the handle is swung into the dotted line position shown in Fig. 14, it will cause the separation of the arms 68 and 69, by means of the levers 73 and 75. Set screws 76 and 77 limit the movement of the arms 68 and 69, while springs 78 and 79 respectively tend to pull these arms together.

It will be seen from Fig. 16 that the frames 65 and 66 are reciprocated alternately, since the ends of the crank shaft 57 are bent in opposite directions. In order to insert a board, such as 29 and 30 in place, the handle 70 is first swung into its dotted line position, so as to permit it to be inserted, but when the boards are inserted it is pulled over into the full line position, thereby permitting the springs 78 and 79 (see Fig. 14) to bring the arms together, thereby bringing the saws 68¹, 68², 69¹ and 69² into engagement with the upper and lower sides of both boards respectively.

The pocket cutting arrangement thus far described operates so that the cuts are made clear to the corners. That is, a side saw will run to its limit and then retract and an end saw will run to the end just vacated by the side saw. Thereupon the other side saw will run into the corner just vacated by the end saw, whereupon the other end saw will run into the corner just vacated by the opposite side saw. This motion continues until the pocket is cut through. It will be observed, however, that the upper and lower end pocket cutting saws operating on any one board, are not in alinement. This makes a shoulder 80 at the end of the longitudinal pulley opening 81 (see Fig. 18). In this same figure the boards 29 and 30 have longitudinal pulley openings 82, transverse dadoes 83 at one end, and oblique dadoes at the other.

45 I claim:

1. In a window jamb machine, a frame, clamping devices carried by the frame for holding the jamb boards apart, a boring device carried by the frame between the clamping devices, the movement of the clamping devices serving to force the boards into engagement with the ends of the boring devices, said boring devices being movable laterally of the clamping devices for forming elongated openings in the boards, and reciprocating dado saws carried by said frame and arranged to be engaged by the boards through the movement of the clamping devices.

2. In a window jamb machine, a frame, clamping devices carried by the frame for holding the jamb boards apart, a boring device carried by the frame between the clamping devices, the movement of the

clamping devices serving to force the boards into engagement with the ends of the boring devices, said boring devices being movable laterally of the clamping devices for forming elongated openings, reciprocating dado saws carried by said frame and arranged to be engaged by the boards through the movement of the clamping devices, pocket cutting saws, and means for bringing said boards into engagement with the pocket cutting saws.

3. In a window jamb machine, a frame comprising a bed plate having a rack, a carriage slidably disposed on said bed frame and being provided with a pinion arranged to engage the rack, a crank for said pinion, boring tools carried by said carriage, means for operating said boring tools, means for moving said boring tools relatively to said carriage and longitudinally of the bed plate, reciprocating dado saws carried by said carriage, and means for reciprocating said dado saws.

4. In a window jamb machine, a main frame, a bed plate carried thereby, a dado cutter frame revolubly supported on said bed plate, a shaft carried by said main frame, an eccentric on said shaft, a rod carried by said eccentric and arranged to extend through said dado cutter frame, the axis of rotation of the dado cutter frame and the axis of the rod being coincident, a bell-crank lever carried by said dado cutter frame and having connection with said rod, a link carried by said bell-crank lever, a slideable frame carried by said dado cutter frame and being pivotally connected to said link, and saws carried by said slideable frame.

5. In a window jamb machine, a frame, a clamping device carried by said frame and having members for holding the opposed jamb boards apart, a dado cutter device disposed between the clamping device and arranged to be engaged by the boards through the movement of the clamping device.

6. In a window jamb machine, an elongated frame, a plurality of clamping devices disposed at intervals along said frame, each of said clamping devices having members for holding the opposed jamb boards apart, dado cutter devices disposed between the clamping devices and arranged to be engaged by the boards through the movement of the clamping members, a rock shaft extending longitudinally of said elongated frame and means connected with the rock shaft for operating each of said clamping devices simultaneously.

7. In a window jamb machine, an elongated frame, a plurality of clamping devices disposed at intervals along said frame, each of said clamping devices having members for holding the opposed jamb boards apart, dado cutter devices disposed between the clamping devices and arranged to be en-

- gaged by the boards through the movement of the clamping members, a rock shaft extending longitudinally of said elongated frame, means connected with the rock shaft 5 for operating each of said clamping devices simultaneously with the other clamping device, and means for varying the relative positions of said clamping devices with respect to each other.
10. 8. In a window jamb machine, an elongated frame, a plurality of clamping devices disposed at intervals along said frame, each of said clamping devices having members for holding the opposed jamb boards apart, 15 dado cutter devices disposed between the clamping devices and arranged to be engaged by the boards through the movement of the clamping members, a rock shaft extending longitudinally of said elongated 20 frame, means connected with the rock shaft for operating each of said clamping devices simultaneously with the other clamping device, means for varying the relative positions of said clamping devices with respect 25 to each other, said last named means comprising a bed plate carried by the frame, a carriage slidably disposed on said bed plate and arranged to support one of said clamping devices, and means for moving the carriage 30 along the bed plate.
9. In a window jamb machine, a frame, a carriage movable longitudinally of said frame, a clamping device carried by said carriage, a clamping device carried by said 35 frame, each of said clamping devices having members for holding the opposed jamb boards apart, dado cutter devices disposed between the clamping members and arranged to be engaged by the boards through 40 the movement of the clamping members, and means for moving said carriage toward and away from the clamping device carried by the frame.
10. In a window jamb machine, a frame, a carriage movable longitudinally of said frame, a clamping device carried by said carriage, a clamping device carried by said frame, each of said clamping devices having members for holding the opposed jamb boards apart, dado cutter devices disposed 45 between the clamping members and arranged to be engaged by the boards through the movement of the clamping members, means for moving said carriage toward and away from the clamping device carried by 50 the frame, and means for simultaneously opening and closing the clamping members of both of said clamping devices.
11. In a window jamb machine, a frame, a clamping device carried by said frame and 55 having members for holding the opposed jamb boards apart, a dado cutter frame revolvably supported on said frame, upper and lower reciprocating cutters carried by said dado cutter frame for engaging the respective boards of the jamb, and means for adjusting the revoluble dado cutter frame to simultaneously vary the position of both of 60 said reciprocating cutters.
12. In a window jamb machine, a main 65 frame, a bed plate carried thereby, a dado cutter frame revolvably supported on said bed plate, upper and lower reciprocating cutters carried by said dado cutter frame, clamping devices, each having a pair of upper and a pair of lower jaws, each pair of jaws being arranged to hold one of the jamb boards, the dado cutters being disposed between said pairs of jaws and means for moving said pairs of jaws toward each other, 70 thereby bringing the boards into engagement with the dado cutters.

JOHN E. EISELE.
